COMPOUND ROTARY PUMP.

1,111,307.

Specification of Letters Patent. Patented Sept. 22, 1914.

Application filed July 30, 1913. Serial No. 781,993.

To all whom it may concern:

Be it known that I, CHARLES E. HULTGREEN, a citizen of the United States, residing at Oakland, in the county of Alameda and State of California, have invented new and useful Improvements in Compound Rotary Pumps, of which the following is a specification.

This invention relates to a rotary pump. 10 The purpose of this invention is to provide a simple, compact, cheaply manufactured pump of the rotary type, which is adapted for various purposes such as pumping water, oil or any liquid matter, as well 15 as air and vacuum.

The main object of this invention is to construct a pair of revolving transmission rotors having large contact surfaces provided with means to prevent leakage between the rotors and containing casing, and which are also provided with peculiar-shaped recesses which will considerably increase the capacity of the pump, and which will also permit a steady flow of liquid as 25 they revolve at both high and low speed, thus eliminating pulsating or knocking movement generally occurring in reciprocating pumps.

The invention consists of the parts and 30 the construction and combination of parts as hereinafter more fully described and claimed, having reference to the accompanying drawings, in which—

Figure 1 is a vertical central section. Fig. 35 2 is a plan view, partly in section.

Referring to the drawings: A indicates a casing in which is appropriately journaled, as at 2 and 3, a pair of shafts 4 and 5, upon which is suitably secured, as at 6 and 7, a 40 pair of transmission rotors or pistons 8 and 9. One-half of each piston member is considerably reduced in diameter, as indicated at 10, and the pistons are so positioned with relation to each other that the large diameter of one piston will contact with the smaller diameter of the opposite piston. For the purpose of preventing leakage between the contacting surfaces of the pistons, as 45 these intermesh in their revolution with relation to each other, a plurality of slots have been cut across the faces of the pistons upon the small diameter of same, as indicated at 11. Mounted in these slots are a 50 similar number of bars 12, and interposed 55 between the bars and the bottom of the slots,

for the purpose of yieldably supporting the bars, are a suitable number of springs 13.

Extending through the ends of each bar, as indicated at 14 and 15, is a pair of headed retaining bolts 16 and 17, the ends of which are threaded and secured in the pistons. The outward movement of the bars 12 within the slots can thus be adjusted, and the bars are further prevented from being entirely projected out of the slots by the 65 springs 13.

Mounted upon the outer end of the shafts 4 and 5 is a pair of transmission gears 4^a and 5^a, and a driving pulley (not here shown) may be mounted on the outer end 70 of the shaft 4 for the purpose of transmitting revolving movement through the gears 4^a and 5^a for the purpose of revolving the pistons 8 and 9 with relation to each other.

The driving gears 4^a and 5^a may be suitably inclosed by a secondary casing, indicated at B, which may be partly filled with a lubricant so as to automatically lubricate the revolving parts. The main casing A, within which the pistons 8 and 9 are revolvably mounted, is provided with an inlet opening 18 on the lower side, and an outlet opening 19 on the upper side.

In operation it can readily be seen that when the rotors revolve in opposite directions, as indicated by small arrows *a* and *b*, suction will be produced by the larger diameters of the pistons, as these pass the inlet opening. The liquid will thus be elevated by the suction into the annular spaces 85 formed between the smaller diameters of the pistons and the casing, as indicated at 20, and will finally be discharged from the pump through the outlet opening in a similar manner. The piston 9 is here shown as 90 taking water, while the larger diameter of piston 8 is discharging water, through the outlet opening 19. The yielding packing bars mounted in the opposite pistons will 95 always form a perfectly tight joint between the rotors so as to prevent any leakage between same. The fluid circulated by the pump will thus be admitted through the opening 18 and caught in the recesses between the revolving vanes, to be finally discharged at 19; the wide, outer convex faces of the pistons being sufficient to prevent leakage around the outer surfaces of the pistons and the casing.

The pump here shown is neat in appear- 110

ance, compact in construction and reliable in action, and takes less space than so-called gear pumps of similar capacity. The wide, convex surfaces formed between the pistons and the casings, together with the packing bars interposed between the contacting surfaces of the rotors as these intermesh, permit of high efficiency as leakage is practically eliminated. Furthermore, a constant, even discharge is always maintained as one recess filled with water begins its discharge at approximately the same moment that the opposite recess is completing its discharge; an even flow is thus always maintained regardless of the speed of the pump, and pulsation or knocking movements, to which reciprocating pumps are generally subjected, are entirely eliminated.

Having thus described my invention, what I claim and desire to secure by Letters Patent, is:

In a pump, a casing having an inlet and an outlet, a pair of pistons in the casing, each of said pistons having a smooth uninterrupted large peripheral portion and a substantially semi-circular reduced periph-

eral portion which forms a single pair of abutments that are peripherally curved and have concave bases on their inner sides which merge into the peripheries of the reduced portions whereby the outer curved side portion of the abutment of one piston will snugly fit in the concavity at the inner side of the corresponding abutment on the other piston, and a series of packing bars extending across the reduced peripheral portions of each of the pistons, the outermost packing bars being located at the points of juncture of the concave portions of the inner sides of the abutments with said reduced piston portions so as to contact with the adjacent end portion of the larger peripheral portion of the other piston before the abutments are engaged and before they are disengaged from each other.

In testimony whereof I have hereunto set my hand in the presence of two subscribing witnesses.

CHARLES E. HULTGREEN.
